US0D1105724S

(12) **United States Design Patent** (10) **Patent No.:** **US D1,105,724 S**
(45) **Date of Patent:** **** Dec. 16, 2025**

(54) **SHOE**

(71) Applicant: **adidas AG**, Herzogenaurach (DE)

(72) Inventors: **Ladan Salari-Sharif**, Portland, OR (US); **Yuanjie Li**, Lake Oswego, OR (US); **Christian Manuel Arias Delgado**, Portland, OR (US); **Zachary C. Coonrod**, Portland, OR (US)

(73) Assignee: **adidas AG**, Herzogenaurach (DE)

(**) Term: **15 Years**

(21) Appl. No.: **29/997,089**

(22) Filed: **Apr. 4, 2025**

Primary Examiner — Amber R Stiles

Assistant Examiner — Christen Pilar Brown-Lorrig

(74) Attorney, Agent, or Firm — Sterne, Kessler, Goldstein & Fox P.L.L.C.

(57) **CLAIM**

The ornamental design for a shoe as shown and described.

DESCRIPTION

FIG. 1 is a top perspective view of a shoe showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the shoe that form no part of the claimed design.

1 Claim, 7 Drawing Sheets
